CIRCUIT BREAKER OPERATING SYSTEM

Alexander C. Boisseau, Lansdowne, Benjamin S. Beall, Upper Darby, Edward J. Frank, Springfield, and Roger W. Lowery, Aldan, Pa., assignors to General Electric Company, a corporation of New York

Application November 30, 1944, Serial No. 565,834

9 Claims. (Cl. 200—81.4)

1

Our invention relates to circuit breaker operating systems, and more particularly to a system for effecting high speed operation of circuit breakers controlling large amounts of electrical energy. Specifically our invention is an improvement on copending Thumim et al. application, Serial No. 367,789, filed November 29, 1940, and assigned to the same assignee as the present application.

In order to eliminate the fire hazard, circuit breakers have been satisfactorily designed which do not utilize oil or other inflammable liquid for arc-extinguishing purposes but instead employ a blast of fluid, such as air or other gas, to extinguish the arc formed both when the circuit is broken between the relatively movable contacts of the circuit breaker and also during the closing operation of the circuit breaker to prevent the formation of any arc at this time. However, the value of any circuit breaker, whether or not it be of the fluid-blast type, lies in its ability to interrupt a circuit at the proper time and in the proper manner. Without a satisfactory operating and control system for such a circuit breaker, its value is largely lost for, if the control of the circuit breaker in the manner intended is not obtained, many undesirable conditions may result. Numerous control systems have been designed for satisfactorily controlling circuit breakers of the fluid-blast type. Our invention is specifically concerned with providing an operating or control system for a gas-blast circuit breaker which controls larger amounts of electrical energy than were heretofore thought possible, such as in the neighborhood of three and one-half million kva. or more. When such circuit breakers are used on high-voltage systems, because of the necessity of providing sufficient electrical clearance between phases, it is customary to design them as single-pole units and to use a plurality of these units for a polyphase circuit breaker. It becomes necessary, therefore, to operate and interlock these units so that they will act as a single circuit breaker.

Accordingly it is an object of our invention to provide a new and improved operating system for an electric circuit breaker capable of controlling large amounts of electrical energy which is rugged in construction, simple in design and provides satisfactory operation in every respect.

It is another object of our invention to provide a new and improved operating and control system for a polyphase fluid blast circuit breaker in which a plurality of single pole units are arranged to operate as a single polyphase circuit breaker.

2

Further objects and advantages of our invention will become apparent as the following description proceeds and the features of novelty which characterize our invention will be pointed out with particularity in the claims annexed to and forming a part of this specification.

For a better understanding of our invention reference may be had to the accompanying drawings in which Fig. 1 is a perspective view of a commercial embodiment of an electric circuit breaker embodying our invention; Fig. 2 is a schematic diagram, partly in section, of the circuit breaker operating system embodying our invention showing primarily the pneumatic and mechanical connections with the electrical connections omitted for the sake of simplicity; and Fig. 3 schematically illustrates the electrical circuits for the operating system disclosed in Fig. 2.

Referring now to Fig. 1 of the drawing, there is illustrated a polyphase circuit breaker generally indicated at 1 comprising a plurality of single pole units 2, 3 and 4, respectively. Each of these units, 2, 3 and 4, includes a pair of relatively separable arcing or interrupting contacts schematically illustrated at 5 and 6 in Fig. 2. Each set of arcing or interrupting contacts associated with the respective interrupting units 2, 3 and 4, is serially connected with a set of isolating contacts the movable contact arms of which are designated as 7, 8 and 9, respectively. Each of the interrupting units 2, 3 and 4 is supported from a framework generally indicated at 10 by a tripod arrangement of insulators designated at 11, the poles 2, 3 and 4 being spaced the desired distance for proper electrical clearance. Isolating contact arms 7, 8 and 9 are pivotally mounted on horizontal pivots generally indicated at 12 and are gear-driven from rotatable insulators 13, one associated with each disconnecting contact arm 7, 8 and 9. Each disconnecting contact arm is adapted to engage with a cooperating stationary contact designated by the numeral 14 mounted on a suitable insulator 15 supported from framework 10. Each of the contacts 14 is electrically connected to an associated line terminal 16. The other line terminals 17 for the various poles of the polyphase circuit breaker are indicated as extending from the top of each interrupting unit 2, 3 and 4.

Suspended from supporting framework 10 are a plurality of tanks 18, 19 and 20, respectively, associated with poles 2, 3 and 4. These tanks are each adapted to contain a source of fluid under pressure such as air or other gas. Preferably these tanks are interconnected by a conduit 21

shown in Fig. 2. The operating and control system of our invention is also mounted on framework 10 and will be described in greater detail hereinafter. It will be observed that the polyphase circuit breaker employing the operating mechanism of our invention is particularly adapted for installation out of doors, in which case the isolating contacts comprising external switch blades or contact arms 7, 8 and 9 may be constructed in accordance with the invention disclosed and claimed in copending application Serial No. 559,064, filed October 17, 1944, Frank and Fitzpatrick, now Patent Number 2,426,009, issued August 19, 1947, assigned to the same assignee as the present application.

The specific construction of the circuit interrupting units 2, 3 and 4 schematically illustrated in Fig. 2 forms no part of our invention but is disclosed and claimed in the copending application of Alexander C. Boisseau and Benjamin S. Beall, Serial No. 570,006, filed December 27, 1944, now Patent Number 2,444,765, issued July 6, 1948, assigned to the same assignee as the present application. Each of these interrupting units is identical and interrupting unit 3 which has been shown in section will be briefly described in order more fully to appreciate our new and improved operating and control system therefor. Interrupting head or unit 3, as is mentioned above, comprises an insulating chamber 22 within which relatively movable contacts 5 and 6 are mounted. Both contacts 5 and 6 have been illustrated as movable contacts biased to the closed position by means of springs 23 and 24, respectively. In the closed position of the circuit breaker contacts 5 and 6 are in electrical engagement as shown in Fig. 2 and the contact 5 extends through a nozzle 25 while the contact 6 extends through a nozzle 26. Associated with contact 5 is a fluid motor comprising piston 27. Similarly, associated with contact 6 is a fluid motor comprising piston 28. Pistons 27 and 28 are reciprocal within cylinders suitably mounted in arc extinguishing chamber 22. In the case of circuit interrupting unit 3 fluid under pressure is supplied from the source comprising tank 19 through a relatively short conduit 29 to arcing chamber 22, conduit 29 being branched as indicated at 30 and 31 so as to supply fluid under pressure ahead of each nozzle 25 and 26. The flow of this fluid under pressure, which is preferably air, is controlled by a blast valve generally indicated at 32 closely associated with tank 19. When blast valve 32 is opened contacts 5 and 6 are retracted through nozzles 25 and 26 and a blast of fluid through each nozzle quickly extinguishes the arc drawn between contacts 5 and 6. The fluid blast exhausts to atmosphere through conduit 33. It should be understood that the interrupting units 2 and 4 are also connected by conduits 29 with tanks 18 and 20, respectively. Similarly, a blast valve 32 is associated with each conduit 29. These conduits are all preferably short and of equal length to insure equal intensity and timing of the fluid blasts.

The electrical circuit for each pole of the circuit breaker is completed between terminals 16 and 17 by stationary isolating contact 14, isolating or disconnecting arms, such as 7, 8 or 9, conductor 34, and interrupting contacts 5 and 6.

The disconnecting contact arms 7, 8 and 9, are preferably operated as a unit after the interrupting contacts have functioned. The operating mechanism for these disconnecting contacts has been illustrated as identical with the operating mechanism disclosed and claimed in copending

application, Serial No. 529,670, Boisseau, filed April 5, 1944, now Patent Number 2,445,558, issued July 20, 1948, and assigned to the same assignee as the present application. This mechanism comprises a simple, longitudinally reciprocal operating rod 35 which extends between the outermost poles 2 and 4 of the circuit breaker and which will permit any spacing, such as 20 or more feet between poles. At each end of operating rod 35 is a rack 36. A similar rack 37 is also provided intermediate the ends of rod 35. These racks are adapted to engage spur gears 38, which through rotatable insulators 13 are drivingly connected with bevel gears 39 which mesh with bevel gears 40 rotatably mounted with disconnecting arms 7, 8 and 9, respectively, about horizontal axes 12. It will be obvious that movement to the left of rod 35, as viewed in Fig. 2, will cause the racks 36 and 37 to rotate spur gears 38 and to cause simultaneous opening of the disconnecting contacts of all of the poles of the multipole circuit breaker through simultaneous operation of disconnecting arms 7, 8 and 9.

Any suitable means may be provided for causing reciprocal movement of operating rod 35. In view of the fact that fluid under pressure is already provided in tanks 18, 19 and 20, a fluid operated means for operating rod 35 is preferable, and we have illustrated a circuit breaker opening fluid motor comprising piston 41 and cylinder 42 associated with the left-hand end of operating rod 35. A closing fluid motor comprising piston 43 and cylinder 44 is associated with the right-hand end of operating rod 35. With this arrangement, as is disclosed and claimed in the above mentioned copending Boisseau application, Serial No. 529,670, substantially only tensile forces are applied to operating rod 35 which, accordingly, may be of relatively light construction. The circuit breaker opening fluid motor comprising cylinder 42 and piston 41 is connected through conduit 45, circuit breaker opening valve generally indicated at 46, and conduit 47, to tank 19. Similarly, the circuit breaking closing fluid motor comprising piston 43 and cylinder 44, is connected through conduit 48, circuit breaker closing control valve generally indicated at 49, and conduit 47 with tank 19.

It is essential that the arcing contacts 5 and 6 in each of the interrupting units 2, 3 and 4 of the polyphase circuit breaker are separated and a blast of arc extinguishing air or gas be present adjacent all of the separated contacts before the disconnecting contact arms 7, 8 and 9 are operated. Since each of the sets of disconnecting contacts are individually operable a suitable interlocking means should be provided between the circuit breaker opening control valve 46 and blast valves 32. Such an interlocking means is disclosed and claimed in the above mentioned Thumim et al. copending application, Serial No. 367,789. In the drawing we have schematically illustrated a pneumatic interlock generally designated at 50 which is essentially the same as the pneumatic interlock in the above mentioned Thumim et al. application. The pneumatic interlock 50 comprises three identical cylinders 51, 52 and 53 within which are mounted three identical pistons 54, 55 and 56, respectively. Springs 57 act against one face of pistons 54, 55 and 56 to maintain them in the position indicated in Fig. 2. The opposite faces of pistons 54, 55 and 56 are connected by conduits 58, 59 and 60, respectively, with the blast conduits 29 associated with interrupting units 2, 3 and 4, respectively. Each of

the cylinders 51, 52 and 53 is provided with a large port 61 connected to atmosphere. Cylinders 52 and 53 are interconnected by a conduit 62, while cylinders 52 and 51 are interconnected by a conduit 63. Conduits 62 and 63 are each provided with a branch conduit flowing into a common conduit 64 leading through an electrically operated isolating switch reclosing interlock valve generally indicated at 65 to opening control valve 46. With the pistons 51, 52 and 53 in the normal spring biased position shown in Fig. 2, the ports connecting conduits 62 and 63 with the associated cylinders are in free communication to atmosphere via the large ports 61. When all of the blast valves 32 are opened and fluid under pressure is flowing in each of the conduits 29, pistons 54, 55 and 56 are driven upwardly as viewed in Fig. 2 so that fluid under pressure builds up in conduit 64, for in this position the pistons 54, 55 and 56 are now interposed between conduits 62, 63 and the freely venting exhaust ports 61. Circuit breaker opening valve 46, as in the above mentioned Boisseau application, Serial No. 529,670, is a pneumatically operated valve and is opened when fluid under pressure is built up in conduit 64 and electrically operated isolating interlock valve 65 is in the normally open position indicated, as will be more fully described hereinafter.

From the foregoing description it will be obvious that pneumatic interlock 50 will not permit operation of circuit breaker opening valve 46 until all three pistons 54, 55 and 56 have been moved upwardly beyond all of the ports leading to conduits 62 and 63. If for example, only pistons 54 and 55 move upwardly while piston 56 remains in the position indicated due to failure of the blast valve 32 associated with interrupting unit 4, then the fluid under pressure in conduits 58 and 59 will pass through conduits 63 and 62 and thence to atmosphere through port 61 of cylinder 53. It is obvious then that pneumatic interlock 50 positively prevents the opening of the isolating contacts comprising contact arms 7, 8 and 9 unless all the blast valves 32 have operated and fluid under pressure is flowing in each of the conduits 29. In other words, circuit breaker opening valve 46 cannot be operated to the opening position to cause simultaneous operation of all of the disconnecting arms 7, 8 and 9 until a blast of fluid under pressure is assured within all of the interrupting units 2, 3 and 4, or until the arcs are extinguished at all of the interrupting contacts.

It is usually desirable to lock the operating mechanism of the electric circuit breaker in either its open or its closed position. The locking means for this purpose must be such that it is released prior to the application of any force tending to separate the contacts of the circuit breaker. For this purpose we have illustrated a lock-open means 66 and a lock-closed means 67 arranged in close proximity to the rack 37 associated with interrupting unit 3. Locking means 66 and 67 are substantially identical, lock-open means 66 comprising a locking member 68 pivotally mounted at 69 and connected through a crank arrangement to a piston 70 reciprocally mounted in a cylinder 71. A spring 72 biases piston 70 and consequently locking member 68 into its locking position which is in engagement with roller 73 associated with the right-hand end of rack 37. When the circuit breaker is in other than its fully open position the rack 37 maintains the locking member 68 in the depressed position in-

5 indicated in Fig. 2. The cylinder 71 of lock-open means 66 is connected by means of a conduit 74 with the conduit 48 supplying the circuit breaker closing fluid motor so that whenever the circuit breaker closing valve 48 is opened fluid under pressure will be admitted to cylinder 71 of the lock-open means 66 to move locking member 68 to its released position. A crank arm 75, the purpose of which will be brought out in the description included hereinafter, is fixedly mounted with locking arm 68 so as to also be rotatable about pivot 69.

Lock-closing means 67 comprises a locking arm 76 pivotally mounted about a shaft or pivot 77 and connected by suitable crank means to a piston 78 reciprocal in a cylinder 79. A spring 80 biases piston 78 and consequently locking member 76, into its locking position as shown in Fig. 2, which is in engagement with roller 81 associated with the left-hand end of rack 37. When the circuit breaker is in other than its fully closed position the rack 37 maintains the latching arm 76 in a depressed position analogous to the position of locking arm 68, shown in Fig. 2. The cylinder 79 of lock-opening means 67 is connected by means of a conduit 82 with the conduit 45 leading to the circuit breaker opening fluid motor so that whenever the circuit breaker opening valve 46 is opened fluid under pressure will be admitted to cylinder 79 of lock-open means 67 to move locking arm 76 to its released position. A crank arm 83, the purpose of which will be brought out in the description hereinafter, is rotatable about shaft 77 in fixed relationship with respect to locking arm 76.

40 If desired suitable dashpot means, generally indicated at 84 and 85 in Fig. 2, may be provided one at either end of operating rod 35. The dashpot means 84 is illustrated as being engageable by the rack 38 associated with interrupting unit 4 to cushion the operating mechanism as the circuit breaker reaches its closed position. Similarly, the dashpot means 85 is engaged by the rack 36 associated with interrupting unit 2 to cushion the operating mechanism as the circuit breaker reaches its open position.

45 Preferably the movement of operating rod 35 may be used to control limit switches. Accordingly we have illustrated a circuit breaker "a" switch 86, associated with the left-hand rack 36, which is closed when the circuit breaker is closed and open when the circuit breaker is open. Similarly, a "b" switch 87 is provided adjacent the right-hand rack 36 so as to be open when the circuit breaker is closed and closed when the circuit breaker is open. These limit switches 86 and 87 are operated by the racks 36 in a manner which is obvious from Fig. 2.

50 Operating rod 35 may also control the closing cut-off switch generally indicated at 88. This closing cut-off switch 88 is in many respects substantially identical with the closing cut-off switch disclosed and claimed in Boisseau Patent 2,346,147, granted April 11, 1944, and assigned to the same assignee as the present application. This closing cut-off switch comprises an electromagnet including magnetic core 89 having associated therewith a winding 90. In addition this electromagnet also includes a pair of pivotally mounted armatures 91 and 92. These armatures are normally biased away from core 89 by springs 93 and 94, respectively. Armature 91 is a relatively light armature which always is within the coercive range of the electromagnet associated therewith, while armature 92 is a heavy armature

which can be moved outside the coercive range of the associated electromagnet when free to move under the influence of spring 84. When armature 91 is moved into the position indicated in Figs. 2 and 3 it closes a set of contacts 85. On the other hand, when armature 92 is moved under the influence of spring 94 to its extreme position it closes contacts 86. The armature 92 may be moved to the position indicated in Fig. 2 by two different means. The first of these means is a mechanical means and comprises a lever 87 rotatable with locking arm 76. When locking arm 76 moves to its locking position indicated in Fig. 2, arm 87 moves armature 92 to the position indicated in Fig. 2 whereby it may be held in that position by the energization of winding 80. The second means for moving armature 92 into the coercive range of the associated electromagnet is a pneumatic means comprising piston actuated plunger 98 reciprocal in a cylinder 99 connected to conduit 82. Plunger 98 is normally biased by a spring 100 to the position indicated in Fig. 2. Whenever circuit breaker opening valve 46 is open, fluid under pressure from tank 19 moves piston operated plunger 98 into engagement with an extension 101 of heavy armature 92 so as to move armature 92 to the position indicated in Fig. 2. For a more detailed description of closing cut-off switch 88 attention is directed to the above mentioned Boisseau Patent 2,346,147.

As has been mentioned above, in order that relatively short air blast conduits 29 of equal length may be utilized to provide substantially equal fluid blasts at the interrupting units 2, 3 and 4, three similar individual blast valves 32 are provided. It is desirable that these three blast valves are operated simultaneously and to this end a control arrangement therefor which will be described in greater detail hereinafter is provided.

The blast valves 32 are very similar to the blast valves disclosed in United States Letters Patent 2,315,991, Thumim, granted April 6, 1943, and assigned to the same assignee as the present application. Since the three blast valves 32 are all identical, only one of them, namely the one associated with interrupting unit 3, has been shown in section. Each of the blast valves 32 comprises a valve member 102 adapted to control the flow of fluid from the source such as tank 19 to conduit 29. Valve member 102 is connected to a piston 103 reciprocatingly mounted in a cylinder 104 formed integrally with the body of the blast valve 32. Suitable spring means 105 tend to bias valve member 102 to a closed position. To open blast valve 32 a pilot valve generally indicated at 106 is provided which allows fluid such as air under pressure from tank 19 to enter cylinder 104 above piston 103 through conduit 107. This fluid under pressure, by virtue of the larger area of piston 103 relative to the area of valve member 102, forces valve member 102 away from its seat to provide a path between source 19 and interrupting unit 3 or between sources 18 and 20 and interrupting units 2 and 4, respectively, in the case of the other poles of the circuit breaker. Fluid such as air or gas in the space below piston 103 is vented through port 108 so that high speed operation of the blast valve 32 may be obtained. When pilot valve 106 is closed the space in cylinder 104 above piston 103 is vented to atmosphere through a port 109 in pilot valve 106 so that air under pressure, which is admitted below piston 103 through port 108, forces the valve member 102 to its closed position. By this arrangement

both opening and closing of the blast valves 32 is rapid and positive due to the action of fluid under pressure on both sides of pistons 103.

Pilot valve 106 has been illustrated as of the balanced pressure type including a piston 110. Operation of pilot valve 106 is obtained through operation of a control valve member 111. Whenever control valve member 111 is opened the pressure acting on piston 110 is unbalanced and pilot valve 106 is moved to the open position. The control valve member 111 for each blast valve 32 is adapted to be operated either electrically or pneumatically and accordingly is connected to a piston 112 reciprocal in a cylinder 113. A solenoid comprising an armature 114 is also connected to control valve 111. A suitable spring 115 biases control valve member 111 to the closed position. The solenoid comprising armature 114 for the blast valve 32 includes a winding 117. The solenoids comprising armatures 114 associated with the blast valves 32 for controlling the blast fluid in the outer interrupting units 2 and 4 include windings 116 and 118, respectively, which windings are also illustrated schematically in Fig. 3 and will be described in greater detail in connection with the control circuit therefor. A pneumatically operated blast valve seal-in switch 119 for controlling contacts 120 is provided adjacent blast valve 32 associated with interrupting unit 2. Whenever blast valve 32 associated with interrupting unit 2 is open fluid under pressure flowing in conduit 107 will cause blast valve seal-in switch 119 to bridge contacts 120.

In order to be sure that the circuit interrupter is not operated unless the pressure in tanks 18, 19 and 20 which are suitably interconnected by conduit 21 is sufficiently high, we have provided a plurality of pressure responsive switches 121, 122 and 123, respectively. Pressure responsive switch 121 is a minimum opening pressure switch and is closed when the pressure falls to a value below which it might be unsafe to open the circuit breaker. Pressure responsive switch 123 is the minimum closing pressure responsive switch and is arranged to close its contacts when the pressure drops below a value somewhat above the value for which switch 121 is set. Pressure responsive switch 122 is the minimum reclosing pressure responsive switch which closes its contacts when the pressure falls to a value somewhat above the pressure at which the relay 123 closes its contacts. If minimum opening pressure responsive relay 121 is set to close its contacts at pressures below 290 pounds per square inch, then minimum closing pressure responsive relay 123 will close its contacts when the pressure falls below 285 pounds per square inch, and minimum reclosing pressure responsive device 122 will close its contacts when the pressure falls below 330 pounds per square inch. The reason for this is obvious since a greater amount of fluid under pressure is required to close and open the circuit breaker than merely to open the circuit breaker, and likewise a still greater amount of fluid under pressure is required to safely open, reclose and open the circuit breaker than in either of the other situations.

The pistons 112 associated with each control valve 111 for blast valves 32 may be simultaneously operated by a manual trip device of our invention generally indicated at 124. This manual trip device 124 controls the flow of fluid under pressure from one of the tanks such as 20 through conduits 125, 126, 127, and 128 to the

pistons 112 of the control valves 111 for each of the blast valves 32. It should be understood that Fig. 2 is a diagrammatic representation of our invention and the manual trip device 124 is so arranged as to produce substantially simultaneous operation of the three blast valves 32. When fluid under pressure is admitted to conduit 126 the blast valves 32 are simultaneously actuated. Manual trip device 124 comprises a pilot valve member 128 biased to the closed position by means of a spring 130. A manual trip pull rod 131 is adapted to be connected to pilot valve member 128 through a lever 132 pivotally mounted at 133. A spring 134 normally biases manual pull rod 131 to the position indicated in Fig. 2. Connected to lever 132 is hand trip auxiliary switch 135 which closes contacts 136 when hand trip rod 131 is in the normal position shown and opens contacts 136 when the hand trip rod 131 is pulled to the left, as viewed in Fig. 2. Manual trip device 124 also includes a cylinder 137 within which is reciprocally mounted main hand trip valve 138 which is essentially in the form of a large piston having an extension in the form of a small piston 139 biased to close a port 140 by virtue of spring means 141. Whenever manual pull rod 131 is actuated to open valve 128 fluid under pressure is permitted to flow into port 140 and into an expansion tank or surge chamber 142. If the fluid pressure is sufficiently high for safe operation, for example 290 pounds per square inch relative to values enumerated above, small diameter piston 139 is lifted against the bias of spring 141, accompanied by an influx of pressure air below the main hand trip valve or large piston 138 that is effective to raise the piston valve high enough to permit fluid under pressure to enter conduit 126 so that pistons 112 lift the control valves 111 and cause substantially simultaneous opening of the three blast valves 32. The upward movement of piston 138 rotates a prop 143 which engages an extension of lever 132 to hold open manual rod 131 thereby sealing pilot valve 128 in the open position. The opening operation of the circuit breaker will thereafter occur in exactly the same manner as if the blast valve control valve windings 116, 117 and 118 had been energized.

To close the blast valves rapidly and conserve air or fluid under pressure during a hand trip operation, the hand trip piston valve 138 is closed mechanically during the initial motion of the isolating switch mechanism. This is accomplished by providing a cam 144 rotatable with one of the insulators 13 specifically illustrated in Fig. 2 as with the insulator 13 associated with the isolating contact arm 8. Cam 144 is engageable with roller 145 connected with piston or hand trip valve 138.

During a normal circuit interrupting operation, it is desirable from the standpoint of conserving air to close the blast valves 32 as soon as the disconnecting contacts begin to open. Accordingly we have provided a blast valve cut-off switch generally indicated at 146 which is closed when the circuit breaker is closed and which opens as soon as the disconnecting contact arms 7, 8 and 9 begin to move. Blast valve cut-off switch 146 is substantially identical to the auxiliary switch disclosed and claimed in United States Letters Patent 2,362,313, Schneider, granted November 7, 1944, and assigned to the same assignee as the present application. Blast valve cut-off switch 146 comprises a pivotally mounted switching arm 147 adapted to control

a contact 148. Switching arm 147 is normally biased to the open position by means of a spring 149. A lever 150 pivotally mounted at 151 and having mounted thereon a dog 152 controls the opening and closing of switch 147. Lever 150 is connected by link 153 to spur gear 38 associated with interrupting unit 2. With this arrangement, as is fully described in the above mentioned Schneider patent, the blast valve cut-off switch 146 operates early during both the closing and opening strokes of the disconnecting contact arms 7, 8 and 9.

The circuit breaker opening valve 46 and the circuit breaker closing valve 49 are very similar to the pilot valves 108 for controlling the blast valves 32. Circuit breaker opening valve 46 comprises a main valve member 154 connected to a piston 155 and biased to the closed position by means of a spring 156. When the valve member 154 is in the closed position indicated conduit 45 is connected to atmosphere through a port 157 which is closed by a valve member 158 when valve member 154 is open. Opening valve 46 is of the balanced pressure type and is opened by operation of a pilot valve member 159 which opens port 160 releasing to atmosphere the fluid under pressure acting on one side of piston 155.

Circuit breaker closing valve 49 is identical with circuit breaker opening valve 46 as described thus far and the corresponding parts thereof are designated by the same reference numerals.

Pilot valve member 159 of circuit breaker closing valve 49 is operated by a solenoid comprising winding 161. A spring 162 biases the armature 35 of pilot valve 159 associated with solenoid winding 161 in a downward direction to close pilot valve member 159. A pneumatic seal-in switch 40 for circuit breaker closing valve 49 is provided comprising switch member 163 for controlling contacts 164. Seal-in switch 163 is connected to a piston 165 reciprocal in a cylinder 166. Cylinder 166 is connected to conduit 48 so that whenever circuit breaker closing valve 49 is opened, pneumatically operated seal-in switch 163 bridges contacts 164.

The pilot valve member 159 of circuit breaker opening valve 46 is pneumatically operated by means of a piston 167 connected thereto, which is reciprocal in cylinder 168. A spring 169 biases pilot valve member 159 of circuit breaker opening valve 46 to the closed position. Whenever pressure is built up in conduit 64 and isolating switch reclosing interlock valve 85 is in the normally open position indicated in Fig. 2, pilot valve member 159 is opened to open circuit breaker opening valve 46. Pilot valve member 169 when once opened is held in the open position by a mechanical latching member 170 engaging the member 171 connected to movable piston 167. A spring 172 biases latching member 170 into its latching position. The circuit breaker opening valve 46 is closed when the circuit breaker isolating contacts reach their fully open position and locking arm 88 moves into engagement with roller 73 under the influence of spring 72. This is accomplished by means of a rod 173 attached to piston 70 which is engageable with an extension 174 of latching means 170 to release latching means 170 and consequently cause circuit breaker opening valve 46 to close by closing associated pilot valve member 159. The circuit breaker opening valve 46 and its opening and closing control is not our invention but is disclosed and claimed in copending application S. N. 565,835, Frank et al., filed November 30,

1944, now Patent Number 2,437,086, issued March 2, 1948, and assigned to the same assignee as the present application.

A circuit breaker having serially connected interrupting and isolating contacts in which the interrupting contacts are fluid operated and normally biased to the closed position is inherently adapted to operate as a reclosing circuit breaker, and accordingly there is provided a control arrangement by means of which the circuit breaker may be operated as a reclosing breaker. It will be understood by those skilled in the art that reclosing operation of the circuit breaker, as disclosed in the drawings, may be obtained by preventing the isolating contact arms 7, 8 and 9 from operating, whereupon the interrupting contacts 5 and 6 associated with each interrupting unit 2, 3 and 4 will interrupt the circuit and then will immediately reclose upon cessation of the interrupting blast. The electrically operated isolating switch reclosing interlock valve 65 including a solenoid 175 having a winding 176 is adapted to prevent isolating contact arms 7, 8 and 9 from operating. Normally, isolating switch reclosing interlock valve 65 is open so that fluid under pressure in conduit 64 is free to open pneumatically operated circuit breaker opening valve 46. If, however, winding 176 associated with isolating switch reclosing interlock valve 65 is energized the interlock valve 65 is closed to block the flow of fluid in conduit 64 to circuit breaker opening valve 46 which accordingly cannot be operated. Solenoid 175 also controls a switch 177 normally bridging contacts 178.

The reclosing-trip operation of a circuit breaker consists of two successive openings of interrupting contacts 5 and 6 followed by opening of the isolating contacts. It will be understood that the interrupting contacts might be opened and reclosed more than two times before the isolating contacts are opened. However, we prefer to provide only two successive operations of the interrupting contacts before the isolating contacts are operated, and to this end there is provided a pneumatic reclosing relay generally indicated at 179. This pneumatic reclosing relay controls the time which is permitted to elapse between the opening and reclosing of the interrupting contacts and furthermore conditions the reclosing control circuits for the opening operation of the isolating switch that sequentially follows the first reclosing operation if a persistent fault is present. Actually pneumatic reclosing relay 179 performs four separate functions. First, it deenergizes the blast valve windings 116, 117 and 118 by opening the normally closed switch 180 whereby the interrupting contacts 5 and 6 may reclose in response to a cessation of the fluid blast. Secondly, pneumatic reclosing relay 179 assures reestablishment of a circuit for energizing blast valve windings 116, 117 and 118 by closing a normally open switch 181 which is in parallel or shunt with switch 180, within the short time interval between the time when switch 180 deenergizes the blast valve windings and the arcing contacts reclose. With this arrangement if a fault persists the blast valve windings 116, 117 and 118 will immediately be reenergized, the blast valves opened and the arcing contacts operated to re-interrupt the circuit. Thirdly, the pneumatic reclosing relay assures that the disconnecting arms 7, 8 and 9 are operated following a second successive opening operation of interrupting contacts 5 and 6 by opening normally closed switch 182 which prevents re-energization of isolating switch reclosing interlock 75

winding 176. Fourthly, the pneumatic reclosing relay 179 must restore the switches 180, 181 and 182 to their normal position indicated in Fig. 2 at the end of the pneumatic reclosing relay cycle, say approximately one second, or 60 cycles, in preparation for a possible repeat reclosing cycle. The pneumatic reclosing relay 179 will only be briefly described hereinafter since its specific construction forms no part of our invention but is disclosed and claimed in copending Boisseau and Beatty application, Serial No. 565,833, filed November 30, 1944, and assigned to the same assignee as the present application.

The pneumatic reclosing relay 179, schematically illustrated in Fig. 2, comprises a plurality of cylinders 183 and 184. A rather elaborate piston 185 is reciprocal in cylinder 183 while an ordinary piston 186 is reciprocal in cylinder 184. Pistons 185 and 186 are interconnected by a plurality of links 187, 188 and a pivotally mounted lever 189 rotatable with a shaft 190 mounted on fixed pivots. The pistons 185 and 186 are so interconnected that when piston 185 is at the left-hand end of cylinder 183, piston 186 is at the right-hand end of cylinder 184. A spring 191 in cylinder 184, the tension of which may be controlled by adjustable means 192, normally biases the pistons 185 and 186 to the positions indicated in Fig. 2.

Specially constructed piston 185 includes a port 193 leading from the working face of the piston to an annular chamber 194 intermediate the ends of the piston. When fluid under pressure is admitted to cylinder 183 through conduit 195 the pressure must first build up in bore 193 and annular chamber 194 before the piston begins to move. The piston 185 therefore picks up speed slowly and does not receive a high initial velocity as it might were it impacted by a suddenly released pressure front against a full piston face. After a short initial travel, piston 185 uncovers an opening 196 tapped in the sidewall of cylinder 183 which in this case is illustrated as connected with an accumulator chamber 197, although an orifice alone or none at all may be sufficient for different reclosing times. It is obvious that the size of the accumulator chamber 197 will control to some extent the desired time delay in the operation of pneumatic reclosing relay 179. At approximately two-thirds of the stroke of piston 185 the port 196 is again covered and the speed of piston 185 increases to complete the stroke against the increasing pressure of return spring 191. It is obvious that widely varying traveling time characteristics may be obtained by controlling the bore of opening 196 or the size of accumulator chamber 197.

Rotatable shaft 190 has mounted thereon cams 198 and 199, respectively. Cam 198 is adapted to control switches 181 and 182, while cam 199 is adapted to control switch 180. These cams are arranged so that switch 180 is opened a predetermined time in advance of the closing of switch 181 or the opening of switch 182. At the end of the reclosing cycle spring 191 returns the cams 198 and 199 to their initial positions. In this regard it is desirable that all of the switches 180, 181 and 182 be reset at approximately the same time which may be accomplished in a manner disclosed in the above mentioned Boisseau and Beatty application, Serial No. 565,833.

Pneumatic reclosing relay 179 is supplied with fluid under pressure to cause operation thereof in response to every circuit breaker operation. To this end it is preferably connected with conduit

59 which in turn is connected with one of the blast valve conduits 28. As illustrated in Fig. 2, a time delay reservoir 200 is connected by a check valve 201 with conduit 59. Conduit 185, on the other hand, is connected through a check valve 202 with time delay reservoir 200. Preferably time delay reservoir 200 is provided with an adjustable escape port 203. By proper proportioning of time delay reservoir 200 and escape port 203 control of the initial operation of pneumatic reclosing relay 179 is provided. Check valves 201 and 202 prevent the flow of fluid from accumulator reservoir 200 back to conduit 59 or from cylinder 183 back to time delay reservoir 200.

Under certain conditions it may be desirable to move disconnecting arms 7, 8 and 9 when no fluid under pressure is available to operate the opening and closing fluid motors. To this end a manual operating device generally indicated at 204 is provided. This manual operating device is removable and when employed is associated with the gear 38 for controlling the rotation of the disconnecting arm 8. This manual operating device includes a crank 205 and a gear mechanism including a pinion 206 for meshing with gear 38. Rotation of crank 205 will rotate gear 38 and consequently will operate the disconnecting arms 7, 8 and 9. It is advantageous that this manual operating device also provide means for releasing either the closing locking arm 76 or the opening locking arm 68 prior to applying a driving force on the gear 38. Accordingly there is provided a bell crank 207 pivotally mounted at 208 and a bell crank 209 pivotally mounted at 210. Initial rotation of the hand crank 205 causes the device 204 to tilt bodily about the axis of the pinion 206 during which movement the device's projecting pin 208 engages the crank 207 thereby rotating the locking arm 76 out of engagement with the roller 81. This tilting disengaging movement of the device 204 is arrested when crank 207 engages the fixed stop 212 so that further rotation of the hand crank 205 becomes effective to turn the gear 38 thereby opening the disconnecting arms 7, 8 and 9. Conversely, when manually closing the breaker the initial tilting movement of the device 204 unlatches the locking arm 68, through the agency of bell crank 209, preparatory to picking up the drive between the gear and rack mechanism. The manual operating device 204 forms no part of our invention and is disclosed and claimed in copending Gayer application, Serial No. 565,836, filed November 30, 1944, now Patent Number 2,418,704, issued April 8, 1947, and assigned to the same assignee as the present application.

The electrical control system of our invention is schematically illustrated in Fig. 3. It should be understood that this electrical circuit should be superimposed on Fig. 2 but was omitted from Fig. 2 in order to simplify the drawings. The corresponding electrical portions of Fig. 2 are designated by the same reference numerals in Fig. 3. Both Figs 2 and 3 illustrate the control devices in the operating condition corresponding to Fig. 1, that is, with breaker closed, control bus energized and with tanks charged with compressed air at operating pressure. A source of direct current control potential is schematically designated in Fig. 3 as 213. A suitable switch 214 controls the connection of the source 213 with the control circuits. The "b" limit switch 87, which is open when the circuit breaker is closed, is connected in series with an indicating

means such as a green lamp 215, and a resistor 216, across the potential source 213. When the circuit breaker is open the indicating means 215 will be energized. Similarly, circuit breaker "a" switch 86 is connected in series with indicating means illustrated as a red lamp 217 and resistance 218 across potential source 213. When the circuit breaker is closed as is illustrated in Fig. 2, "a" switch 86 is closed and the red lamp 217 is lighted.

In order to initiate a switching closed operation from remote control panel of the circuit breaker, a manual closing switch 219 is provided which controls the energization of the winding 220 of a blocking relay 221 which controls normally closed contacts 222 and is provided with time delay means 223 to provide a short time delay for reclosing of contacts 222. Closing of switch 219 also energizes winding 80 of the closing cutoff switch generally indicated at 88.

The minimum opening pressure switch 121 controls the energization of an auxiliary relay 224 having two normally closed sets of contacts 225 and 226. Minimum reclosing pressure switch 122 controls the energization of an auxiliary relay 227 having a normally closed set of contacts 228 and a normally open set of contacts 229. The normally open set of contacts 229 are adapted to control the energization of an indicating means generally indicated at 230 so that when the fluid under pressure in the tanks 18, 19 and 28 drops below the value determined by minimum reclosing pressure switch 122 the operator will be apprised of this fact. Minimum closing pressure switch 123 also controls the energization of an auxiliary relay 231 having normally closed contacts 232 and normally open contacts 233. The normally open contacts 233 when closed are adapted to energize an alarm or indicating means 234.

A manually controlled tripping switch 235 is provided which controls the energization of an auxiliary relay 236 having normally closed contacts 237 and normally open contacts 238. Auxiliary relay 236 initiates the tripping operation by energizing the blast valve coils 116, 117, and 118, this tripping circuit thereafter being maintained in an energized condition by seal-in contacts 120 even though manually operable tripping switch 235 is released. It is obvious that the contacts of an automatic protective relay may be substituted for, or shunted around, the tripping switch 235 for service conditions where automatic reclosing is not required.

In order to operate the circuit breaker to the open position in response to an abnormal current condition, a suitable relay (not shown) is provided which controls a switching member schematically indicated at 239 for bridging contacts 240.

A double pole, manual selector switch 241 is provided to determine whether or not the operating mechanism will operate to reclose the circuit breaker after being automatically tripped open. In the position indicated in Fig. 3 reclosing of the circuit breaker will result, whereas if switch 241 is moved to its other position thereby preventing operation of isolating switch interlock valve 65, reclosing of the circuit breaker will not occur because opening of the isolating arms 7, 8 and 9 will take place immediately following interruption by the retracting contacts.

In view of the detailed description included above the operation of the control system will be obvious to those skilled in the art, and a rela-

tively brief description will be included herein-after. The control system of our invention will enable the circuit breaker to perform the following operations. (1) electrically controlled opening operation; (2) electrically controlled closing operation; (3) trip free operation; (4) reclosing trip operation, and (5) hand trip operation.

The opening operation of the circuit breaker consists of a single sequential operation of the arcing contacts in interrupting units 2, 3, 4, and the disconnecting contacts serially connected therewith. Assuming that the circuit breaker is in closed position indicated in Fig. 3 but with the selector switch 241 of Fig. 3 moved to the opposite position from that shown, a tripping operation may be initiated either by closing trip switch 235 or by the bridging of contacts 240 by switch 238 upon operation of a suitable relay connected to switch 238. With the pressure in tanks 18, 19 and 20 being sufficiently high so that all of the minimum pressure relays 121, 122 and 123 are in the positions indicated in Figs. 2 and 3, the blast valve windings 116, 117 and 118 will be energized in response to operation of switch 235 or bridging of contacts 240 and consequently the three blast valves 32 will open. Such opening of blast valves 32 will cause seal in contacts 120 to be closed and also will cause fluid under pressure to flow to each of the interrupting units 2, 3 and 4 to interrupt the circuit at the arcing contacts contained in these units. Simultaneously, air will also flow through conduit 59 to the reclosing relay 178 and to the pneumatic interlock 50. In view of the fact that selector switch 241 is moved to the other position from that shown in Fig. 3, the winding 176 of isolating interlock valve 65 cannot be energized and if fluid under pressure exists in all of the blast valve conduits 28, fluid under pressure flowing through conduit 64 opens circuit breaker opening valve 46. As soon as valve 46 has opened it is held open by latch 170 thereby divorcing subsequent action of opening valve 46 from the pressure in blast valve conduits 28. The opening of circuit breaker opening valve 46 permits fluid under pressure to flow into cylinder 79 to release lock open means 67 and also permits fluid under pressure to enter cylinder 42 of the circuit breaker opening fluid motor. In the meantime, although contact 180 of the pneumatic reclosing relay 178 has opened, it is cut-off switch contact 147 that opens to deenergize the blast valve windings 116, 117 and 118, as a consequence of which blast valves 32 are closed. This is due to having previously set switch 241 to the left. The high pressure air in blast conduits 28 exhausts to atmosphere and the arcing contacts 5 and 6 are reclosed by virtue of the action of springs 23 and 24, respectively. Before arcing contacts 5 and 6 reclose, the disconnecting contact arms 7, 8 and 9 have operated to insert an isolating gap in series with each interrupting head 2, 3 and 4, respectively. When the operating rod 35 connected with the disconnecting arms 7, 8 and 9 has reached the end of its opening stroke the locking member 68 moves into locking position and extension 173 releases latch 170 so that circuit breaker opening valve 46 may close. This arrangement insures that the circuit breaker opening valve 46 remains open until the mechanism travel is completed. Since the contacts 96 are held open by air pressure from the opening control valve flowing through conduit 82 to actuate plunger 98 during the circuit breaker opening operation, it is not possible to energize the

closing control valve 49 while the isolating or disconnecting switch mechanism is open since to accomplish this contacts 96 must be closed.

During an electrically controlled closing operation of the circuit breaker, the interrupting contacts 5 and 6 remain in their normally closed position and only the isolating or disconnecting switch mechanism operates. Assuming that the circuit breaker is in the open position and pressure relays 121, 122 and 123 are in the positions indicated in Figs. 2 and 3, closing of the circuit breaker may be initiated by depressing close switch 219 which causes energization of the winding 80 of closing cut-off switch 88 and a consequent closing of normally open contacts 96. The closing of contacts 96 completes the circuit of winding 161 of circuit breaker closing control valve 49 through contacts 86 which are also normally closed when the circuit breaker is open. The opening of circuit breaker closing control valve 49 closes seal-in contacts 164 and furthermore permits fluid under pressure to flow both to the circuit breaker closing cylinder 44 and to the circuit breaker lock open means 66. The supply of fluid under pressure to the circuit breaker lock open means 66 releases locking member 68 and allows piston 43 to close the disconnecting arms 7, 8 and 9. At the end of the closing stroke the hold closed locking arm 76 moves into locking position and arm 87 mechanically opens cut-off switch 88 to deenergize winding 161 of closing control valve 49. In addition to controlling the condition of contacts 96 winding 80 of closing cut-off switch 88 also acts as an anti-plump device by holding the contacts of the closing cut-off switch 88 open after they have once been separated. As long as the closing control switch 219 remains closed contacts 96 will remain open and no further closing operations of the circuit breaker can occur. The details of the anti-pump device and closing cut-off switch are fully described in Boisseau Patent 2,346,147 referred to above.

An electrically controlled trip free operation of the circuit breaker is merely a closing operation followed immediately by a normal opening operation. This type of operation will occur when the breaker is closed in on a fault. To insure that the opening control circuit can be established before the circuit breaker is completely closed the opening cut-off switch 147 substantially identical with the arrangement disclosed in the Schneider patent referred to above, is provided. With this arrangement and particularly by virtue of dog 152 on switch 146 the opening control circuit is established considerably before the breaker is in the system energizing position. When the disconnecting switches 7, 8 and 9 are opening switch 147 causes the opening control circuit to be deenergized shortly after the start of motion thereby saving considerable air on reclosing trip operations. Since trip free operations normally occur when the circuit breaker is closed on an overloaded system the breaker control circuit is arranged to perform only a straight opening operation immediately after closing. The time delay reclosing blocking relay 221 holds open the single shot reclosing circuit for an interval of one second after the breaker isolating switch has closed. As was mentioned above the closing cut-off switch 88 causing operation of the switch controlling contacts 96 prevents pumping of the circuit breaker. The opening operation is given definite preference over the closing operation by virtue of the fact that contacts 96 are opened pneumatically by piston actuated plunger

88 whenever opening control valve 48 is opened. The reclosing trip operation of the circuit breaker consists of two successive openings of arcing or interrupting contacts 5 and 6 followed by the opening of isolating or disconnecting contacts arms 7, 8 and 9. With the selector switch 241 set in the position shown in Fig. 2 a reclosing operation is initiated by the bridging of contacts 240 by switch 239. Bridging of contacts 240 causes energization of the blast valve windings 116, 117 and 118 with the consequent opening of the blast valves 32 and the bridging of seal-in contacts 120. At the same time winding 176 of isolating interlock valve 65 is also energized through contacts 237, 136, 228, selector switch 241, switch 182, and contacts 222 with the consequent blocking of passageway 64 leading to circuit breaker opening valve 46. The circuit breaker opening control valve 48 cannot operate and consequently the isolating switch contact arms 7, 8 and 9 cannot operate but otherwise the circuit breaker functions the same as in a normal opening operation with the high pressure air in interrupting units 2, 3 and 4 extinguishing the arcs drawn therein. As soon as the reclosing relay 179 begins to operate switch 180 is opened to deenergize the blast valve windings 116, 117 and 118 whereupon the arcing contacts 5 and 6 are permitted to reclose. The reclosing relay 179 continues to function to complete its cycle and shortly after switch 180 is opened switch 181 is closed and switch 182 is opened. The opening of switch 182 deenergizes the winding 176 of isolating interlock valve 65 while the closing of switch 181 reestablishes the blast valve circuit for windings 116, 117 and 118 in parallel with switch 180. Switch 182 must remain open a sufficient time after the interruption of the circuit to insure that relay controlling contacts 240 have dropped out to open switch 239. The reclosing relay 179 controls the time which must elapse before reclosing operation can occur. If the system fault persists the breaker will then perform a straight opening operation since the opening of switch 182 deenergizes winding 176 and permits the isolating interlock 65 to open whereupon the circuit breaker opening valve 46 may be opened and an opening operation as has been described above, occurs. Initial movement of the disconnecting arms 7, 8 and 9 operates switch 146 to deenergize the blast valve windings 116, 117 and 118 with the resultant closing of blast valve 32. In the event that the fault is a temporary one and is cleared by the operation of arcing contacts 5 and 6 the reclosing relay 179 will complete its cycle and reset to the position indicated in Fig. 2 with the breaker remaining in the closed position.

A manual trip operation of the circuit breaker like the electrical opening operation outlined above consists of a single sequential operation of the interrupting and isolating contacts. When manual trip pull rod 131 is actuated pilot valve 129 is opened and if the pressure is sufficiently high to insure a satisfactory opening operation pistons 138, 139 will move upwardly to open the passageway between conduits 125 and 126 whereupon by virtue of pistons 112 the blast valves 32 are opened in exactly the same manner as if windings 116, 117 and 118 had been energized electrically. To close the blast valves 32 rapidly and conserve air during hand trip operations, the hand trip valve comprising piston 138 is closed mechanically during the initial motion of disconnecting arms 7, 8 and 9 by virtue of cam 144

which engages a roller 145. Lever 143 holds pilot valve 129 open once it has been opened until the hand trip valve is closed by cam 144.

It will be apparent to those skilled in the art that our invention is not limited to the particular construction shown but that changes and modifications may be made without departing from the spirit and scope of our invention and we aim in the appended claims to cover all such changes and modifications.

What we claim as new and desire to secure by Letters Patent of the United States, is:

1. In a multipole circuit breaker having serially connected interrupting and isolating contacts for each pole thereof, means including a first fluid motor for each pair of interrupting contacts, a source of fluid under pressure, means including a conduit for each pole of said circuit breaker for connecting said source with each of said fluid motors to open said interrupting contacts, a second fluid motor for opening said isolating contacts, means including a valve for controlling the supply of fluid between said source and said second fluid motor, fluid operated means for operating said valve, fluid conducting means connected to said fluid operated means and having a separate connection to atmosphere for each of said conduits, and separate means associated with each conduit and responsive to a predetermined fluid pressure therein for shutting off the separate connection to atmosphere for the associated conduit and for establishing a connection between the associated conduit and said fluid operated means.

2. In a multipole circuit breaker having serially connected interrupting and isolating contacts for each pole thereof, means including a first fluid motor for each pair of interrupting contacts, a source of fluid under pressure, means including a conduit for each pole of said circuit breaker for connecting said source with each of said fluid motors to open said interrupting contacts, a second fluid motor for opening said isolating contacts, means including a valve for controlling the supply of fluid between said source and said second fluid motor, fluid operated means for operating said valve, fluid conducting means connected to said fluid operated means and having a separate connection to atmosphere for each of said conduits, and separate fluid pressure valve means associated with each conduit and responsive to a predetermined fluid pressure therein for shutting off the separate connection to atmosphere for the associated conduit and for establishing a connection between the associated conduit and said fluid operated means.

3. In a multipole circuit breaker having serially connected interrupting and isolating contacts for each pole thereof, means including a first fluid motor for each pair of interrupting contacts, a source of fluid under pressure, means including a conduit for each pole of said circuit breaker for connecting said source with each of said fluid motors to open said interrupting contacts, a second fluid motor for opening said isolating contacts, means including a valve for controlling the supply of fluid between said source and said second fluid motor, fluid operated means for operating said valve, fluid conducting means connected to said fluid operated means and having a separate connection to atmosphere for each of said conduits, and separate plunger operated valve means associated with each conduit and responsive to a predetermined fluid pressure therein for shutting off the separate connection to atmosphere for the associated conduit and for estab-

lishing a connection between the associated conduit and said fluid operated means.

4. In a multipole circuit breaker having serially connected interrupting and isolating contacts for each pole thereof, means including a first fluid motor for each pair of interrupting contacts, a source of fluid under pressure means including a conduit for each pole of said circuit breaker for connecting said source with each of said fluid motors to open said interrupting contacts, a second fluid motor for opening said isolating contacts, means including a valve for controlling the supply of fluid between said source and said second fluid motor, fluid operated means responsive to the flow of fluid to said first fluid motors for opening said valve, an interlock connected between each of said conduits and said fluid operated means to insure opening of all of said interrupting contacts prior to opening of said isolating contacts, manual means for initiating an opening operation of said circuit breaker, and means for rendering said manual means ineffective unless the pressure of said source is above a predetermined value.

5. In a multipole electric circuit interrupter, an arc interrupting unit including a pair of separable contacts for each pole of said circuit interrupter, a source of fluid under pressure, means including a blast valve for each pole of said circuit interrupter interconnecting said source with arc interrupting units, fluid operated means for each blast valve for initiating the opening operation thereof, and means for effecting substantially simultaneous opening of all of said blast valves comprising a biased closed valve between said source and said fluid operated means, fluid operated means for opening said biased closed valve, manually operable means for controlling the supply of fluid to said last mentioned fluid operated means, and means responsive to the opening operation of said circuit interrupter for closing said biased closed valve against the opening force exerted thereon by said last mentioned fluid operated means.

6. In a multipole electric circuit interrupter, an arc interrupting unit including a pair of separable contacts for each pole of said circuit interrupter, a source of fluid under pressure, means including a blast valve for each pole of said circuit interrupter interconnecting said source with arc interrupting units, fluid operated means for each blast valve for initiating the opening operation thereof, and means for effecting substantially simultaneous opening of all of said blast valves comprising a biased closed valve between said source and said fluid operated means, fluid operated means for opening said biased closed valve, and manually operable means for connecting said source of fluid under pressure to said last mentioned fluid operated means.

7. In a multipole electric circuit interrupter, an arc interrupting unit including a pair of separable contacts for each pole of said circuit interrupter, a source of fluid under pressure, means including

a blast valve for each pole of said circuit interrupter interconnecting said source with arc interrupting units, fluid operated means for each blast valve for initiating the opening operation thereof, and means for effecting substantially simultaneous opening of all of said blast valves comprising a biased closed valve between said source and said fluid operated means, fluid operated means for opening said biased closed valve, manually operable means for connecting said source of fluid under pressure to said last mentioned fluid operated means to open said valve means controlled by said last mentioned fluid operated means for holding said manually operable means in its operated position while said last mentioned fluid operated means is maintaining said valve open, and means responsive to the opening operation of said circuit interrupter for closing said valve against the opening force exerted thereon by said last mentioned fluid operated means.

8. In combination with an electric switch comprising a plurality of relatively movable contacts, a source of fluid under pressure, a fluid motor for producing relative movement of said contacts, a biased closed valve disposed between said source and said fluid motor, fluid operated means for opening said valve, manually operable mechanical means for controlling the supply of fluid to said last mentioned fluid operated means, and mechanical means responsive to the movement of said contacts effected by said fluid motor for shutting off the flow of fluid to said fluid operated means thereby to close said valve.

9. In combination with an electric circuit breaker comprising a plurality of relatively movable contacts, a source of fluid under pressure, a fluid motor for producing relative movement of said contacts, a biased closed valve disposed between said source and said fluid motor, fluid operated means for opening said valve, manually operable mechanical means for controlling the supply of fluid to said last mentioned fluid operated means, mechanically operable means controlled by said fluid operated means for holding said manually operable means in its operated position, and means including a cam responsive to the relative movement of said contacts effected by said fluid motor for shutting off the flow of fluid to said fluid operated means thereby to close said valve.

ALEXANDER C. BOISSEAU.
BENJAMIN S. BEALL.
EDWARD J. FRANK.
ROGER W. LOWERY.
